UNITED STATES PATENT OFFICE.

STEPHEN M. LEWIS, OF SWEET HOME, ARKANSAS.

INCUBATOR.

1,346,717.

Specification of Letters Patent. Patented July 13, 1920.

Application filed April 19, 1920. Serial No. 375,013.

To all whom it may concern:

Be it known that I, STEPHEN M. LEWIS, a citizen of the United States, residing at Sweet Home, in the county of Pulaski and State of Arkansas, have invented a new and useful Incubator, of which the following is a specification.

This invention relates to incubators, one of its objects being to provide an inexpensive but efficient device of this character, which will maintain a desired temperature, will supply necessary moisture and fresh air to the eggs, and will allow the eggs to be turned readily.

15 A further object is to provide an incubator the parts of which can be assembled easily and which can be operated without danger of fire.

Another object is to provide an incubator 20 which can be made of any contour desired and which maintains a constant general warmth.

With the foregoing and other objects in view, which will appear as the description 25 proceeds, the invention resides in the combination and arrangement of parts and in the details of construction hereinafter described and claimed, it being understood that, within the scope of what is claimed, 30 changes in the precise embodiment of the invention shown can be made without departing from the spirit of the invention.

In the accompanying drawings the preferred form of the invention has been shown.

35 In said drawings—

Figure 1 is a central vertical section through an incubator embodying the present improvements.

Fig. 2 is a section on line 2—2, Fig. 1.

40 Fig. 3 is a plan view of a portion of the incubator and showing the hinge of the cover.

Fig. 4 is a plan view on a reduced scale 45 showing a modified form of incubator of a substantially oblong shape.

Referring to the figures by characters of reference 1 designates a suitable support on which is mounted the body 2 of the incubator. This body can be of any desired 50 shape. In the form shown in Figs. 1 and 2 the body is shaped like an ordinary wash tub whereas in the form shown in Fig. 4 it is substantially oblong. Obviously it can be of any other shape desired.

55 The body has a cover 3 hingedly mounted thereon, as at 4 or connected to the body in

any other manner desired and in this cover are one or more ventilating openings 5.

Arranged upon the bottom of the body is a coiled pipe 6 one end of which is extended vertically at the center of the body as shown at 7 and opens into an overflow container 8 having openings 9 in the top thereof. The other end of the coiled pipe extends through an opening 10 in the wall of the incubator body and opens into a container 11 having a drain cock 12. A bracket 13 is connected to and suspended from the body and is adapted to support an oil lamp 14 or other heater whereby the contents of the container 11 can be raised to a desired temperature.

The coiled pipe 6 is embedded within a layer of sand 15 or the like and this layer of sand is adapted to support an egg tray 16 of the usual construction on which may 75 be placed another egg tray 17 which is inverted. These trays can be arranged in pairs so as to be easily lifted out of the body and inverted and replaced. If desired additional trays may be suspended by any suitable means above the trays 16 and 17.

In using the incubator water is placed in the coiled pipe 6, container 11 and upstanding portion 7, the eggs are placed in the trays and the trays deposited on the sand, 85 the incubator closed, and the water in the container 11 is heated by the lamp 14 or other means provided therefor. The heated water will maintain the sand at a high temperature sufficient to insure incubation and 90 a portion of the water will be vaporized, the vapor escaping through the openings 9 and into the body 2.

It will be obvious that an incubator such as described can be very cheaply constructed 95 and will likewise be very efficient in use. The sand will retain the warmth for a considerable period of time and will produce an even distribution of the heat.

What is claimed is:

1. An incubator including a body, a layer of granular heat retaining material covering the bottom of the body, a coiled pipe embedded in said material and having an upstanding end portion in the body and an 105 outwardly projecting portion beyond the body, and means outside of the body for heating the contents of the outwardly projecting end of the pipe, the upstanding inner end of said pipe opening into the body 110 for the escape of vapor.

2. An incubator including a body, a layer

of granular heat retaining material upon the body, said material constituting means for supporting an egg tray, a coiled pipe embedded in said layer of granular material 5 and having an upstanding end portion opening into the body for the escape of vapor, the other end of the pipe projecting through the body, a container upon said outwardly projecting end of the pipe, a drain cock

upon the container, and a heater coöperating 10 with the container.

In testimony that I claim the foregoing as my own I have hereto affixed my signature in the presence of two witnesses.

STEPHEN M. LEWIS.
